PARTS WASHING DEVICE

Edward Lee, Winnipeg, Manitoba, Canada, assignor to
Solv-X Inc., Mississauga, Ontario, Canada

Filed Jan. 25, 1972, Ser. No. 220,723

Term of patent 14 years

Int. Cl. D15—05

U.S. Cl. D49—1 R

Those elements of the disclosure shown in broken lines are for illustrative purposes only and form no part of the claimed design invention.

The side of the parts washing device not shown in the drawing is identical in appearance to that side which is shown. The back of the parts washing device is plain and unornamented.

I claim:

The ornamental design for a parts washing device, as shown and described.
